SIGN PAINTER'S TABLE

George R. Cole, Port Huron, Mich.

Application January 15, 1937, Serial No. 120,656

3 Claims. (Cl. 311—52)

This invention relates to improvements in sign painters' tables.

An object is to provide a sign painter's table which is readily adjustable so as to vary the length thereof as may be desired and so as to vary the width thereof as may be desired. More particularly, an object is the provision of a sign painter's table having extensions which may be secured to each of its four sides to increase the size of the table and having further extensions which may be secured to its ends to increase indefinitely the length of the table.

Various meritorious features relate to the improved construction which permits of the attachment of extensions to the four sides of the table and of the alignment of such extensions therewith and to the particular construction for supporting the table top detachably upon the adjustable supporting frame and in such manner to accommodate the extensions for the table top in a convenient manner whereby they may be readily connected or disconnected therefrom and whereby the table top may be quickly disassembled for storage and transportation and quickly assembled and built to any convenient size for use. The construction is such that the complete table top as a size to which it has been built, presents a smooth rigid surface on which to work, and the sections making up the same and supporting the same are of relatively small size in order that they may be conveniently arranged for storage or transportation in compact bundles.

Other objects, advantages, and meritorious features of my invention will more fully appear from the following description, appended claims, and accompanying drawings, wherein:

Figure 1 is an end elevation of a table embodying my invention.

Fig. 2 is a rear elevation of the table top and the upper portion of the supports therefor.

Fig. 3 is a sectional view taken on the line 3—3 with the table top elements separated from the supports and the supports partially disassembled

to more completely illustrate the construction and method of assembling, and

Fig. 4 is a perspective of an end portion of one stringer element and an extension therefor.

This improved table comprises a base made up of a pair of supporting standards 10 which may be arranged in spaced apart relationship in any convenient manner. The standards are of such a character that the table top carried thereby may be raised and lowered and may be adjustably tilted to any desired angle convenient for work-

ing thereon. In the drawings I have illustrated one type of adjustable standard which is adaptable for use. The invention concerns itself primarily with the table top and its supports rather than with the particular adjustment of the standards, but the standard is made up of a lower portion which is stationary and an upper portion 12 which may be raised and lowered with respect thereto. The upper portion 12 may be provided with a rack 14 and pinions 16 mounted upon a shaft 18 extending between the two standards which is provided to raise and lower the upper portions 12 of the standards. The shaft may be provided with a hand wheel 20 by means of which it may be rotated. The shaft may be a telescoping shaft to accommodate for varying the spacing between the standards. The upper portions 12 of the standards may be provided with a series of teeth 22 and latch elements 24 shown in Fig. 2 may be pivoted to the lower portions of the standards to be swung into engagement with such teeth to vary the vertical adjustment.

There is secured to the upper end of the upper portion 12 of each standard a transversely extending table top supporting frame. As illustrated, this supporting frame may be made up of three sections shown more particularly in Fig. 3. In this figure of the drawings I have shown a transverse supporting element 26 and a plate 28 adapted to be bolted or otherwise secured thereto and provided with an arcuate guideway 30. The elements 28 and 26 will be suitably secured together with the element 28 on the inside as shown particularly in Fig. 2. Bolts 31 serve as journals pivotally securing said assembled elements 26 and 28 to the upper ends of the standard portions 12 as shown particularly in Fig. 2. The upper portion of each standard element 12 is built out as at 32 and a tightening screw 34 is mounted therein and extends through the slot 30 of element 28 and is provided with a hand wheel portion for positioning the table top at angular positions about the bolts 31 as horizontal pivots.

To complete the transverse supporting frame assembly there is a sub-frame element 36 which is adapted to superimpose the support 26 and to be detachably connected therewith. It is shown as provided with plates 38 which overlap the transverse support 26 and are connected by thumb screws 40 shown in Fig. 1 therewith. This sub-frame element is provided at its ends and beyond the ends of the supports 26 with a pair of parallel guide plates 42 and bolts 44 to detachably secure end extensions 46 thereto.

These guide plates, bolts, and end extensions are shown separated in Fig. 3. The assembly is shown complete in Fig. 2. The ends of the extensions 46 are slotted as at 48, as illustrated in Fig. 2. This slot is provided to receive the bolts 44 therethrough. The bolts may be provided with wing nuts for convenient tightening and extensions are shown as stepped so that one portion abuts the ends of the element 36 while the other portion overlaps the same within the guide-ways 42.

The table top supporting frame assembly for the table top proper is made up of the elements 26, 28 and 36. The extensions 46 are used as desired and will not be used merely to support the table top proper. The table top proper hereinafter referred to as the table top is indicated as 50 and may be made up of a plurality of sections secured together and provided with lengthwise extending supporting elements 52, which elements are provided at each end with plates 54 that are slotted to receive fastening bolts 56 over the transverse supporting frame 36 as shown in Figs. 1 and 3. Through the means of these plates and bolts the table top 50 is secured to its transverse support and yet it is detachably removable therefrom.

This table top is provided with extensions at the top and bottom at each end. To accommodate these extensions improved means is provided to secure the same thereto. The table top is provided with depending guides 58 which depend within the space between the table top and the element 36 as shown. A relatively wide guide 57 depends from the middle of the table and other guides 58 are aligned therewith at opposite ends of the table. The end guides may be provided with thumb screws 60 as shown in Fig. 2. Stringers 62 are detachably receivable within these guides. As there are three guides adjacent to the top of the table and three guides adjacent to the bottom of the table there are four stringer elements 62 receivable within these guides and projecting beyond the ends of the table as shown particularly in Fig. 2. These stringers 62 are adapted to support table side sections 64 which serve as end extensions of the table. These end wings are secured as end extensions to the table and held to the stringers by means, such as turn buttons 66, shown in Fig. 2. Each end extension is lined up with the end of the table by a pilot pin 68 receivable within a guide 70. A thumb screw 72 may be provided if desired.

The table is provided with top and bottom wings 74. These top and bottom wings are secured to the end extensions 46 of the transverse support assemblies. This may be accomplished by providing plates 76 on the top and bottom wings notched to be received over bolts 78 provided with thumb nuts 80 as shown in Figs. 1 and 3. These top and bottom wings may be aligned with the end wings by pins 82 secured to the end wings and engaging in guides 84 upon the top and bottom wings. Each top and bottom wing may be provided with pins 86 adapted to be received within guides 88 in the table top and the thumb screws 90 may be provided to tighten the same in place as shown in Fig. 3.

If desired an additional supporting base element similar to 10 may be provided and additional table top sections may be added on to the ends of the table top and wings heretofore described. In Fig. 2 there is shown such an additional table top section indicated generally as 92. This table top section is not particularly de-

scribed but in order to support the same and line it up with the extended table top heretofore described the stringers 62 are provided with guides 94 as shown in Figs. 2 and 4. Stringer extension 96 may be detachably secured to the stringers 62 within these guides 94 by the bolts 98 received within the slots 100 of the extensions 102 as shown in Figs. 2 and 4 and thumb nuts 104 may be provided to securely fasten the same in position. The wing 64 which connects up with this additional table extension may be provided with guides 106 to receive locating pins 108 on the additional extension to maintain the alignment. This apparatus might be continued indefinitely.

It will be apparent that through the means hereinabove described it is possible to provide a table of limited size such as is shown in the table top proper 50 mounted upon the transverse supports or that the top and bottom wings and end wings may be secured thereto or even additional end extensions may be added thereon to increase the capacity of the table.

What I claim is:

1. A sign painter's table comprising a base provided with a pair of transverse supports, a table top sub-frame element superimposing in alignment each transverse support and projecting beyond each end thereof, guide means depending from each sub-frame element adjacent to each end thereof beyond the end of its transverse support, means detachably connecting each sub-frame element with its transverse support, a table top detachably secured to the sub-frame elements, a pair of end extensions for each sub-frame element, each end extension having one end portion adapted to be received within the guide means at such end of the sub-frame element underneath said sub-frame element, and having its opposite end portion adapted to abut against the end of the sub-frame element and form an aligned extension thereof, means detachably securing each end extension to its sub-frame element within said guide means, a table top wing supported upon the end extensions at the top of the table top, a table top wing supported upon the end extensions at the bottom of the table top and means detachably securing each table top wing to its supporting end extensions.

2. A sign painter's table comprising a base provided with spaced apart transverse supports, a table top sub-frame element superimposing in alignment each transverse support and projecting beyond each end thereof, means detachably connecting each sub-frame element to its transverse support, a table top detachably secured to said sub-frame elements, guide means depending from each sub-frame element adjacent to each end thereof and beyond the adjacent end of its transverse support, a fastening bolt depending from each sub-frame element within each of said guide means, a pair of end extensions for each sub-frame element, each end extension being of a stepped formation and having one end portion adapted to be received within said guide means underneath said sub-frame element and slotted to receive said fastening bolt and having its opposite end portion adapted to abut against the end of said sub-frame element and form an aligned extension thereof, a table top wing supported upon the end extensions at the top of the table top, a table top wing supported upon the end extensions at the bottom of the table top, guide plates carried by said wings adapted to,

overlap said end extensions, and means adapted to detachably engage said guide plates to the end extensions to secure the wings thereto.

3. A sign painter's table comprising a base having a pair of spaced apart transverse supports, a table top sub-frame element superimposing in alignment each transverse support and projecting beyond each end thereof, guide means depending from each sub-frame element adjacent to each end thereof and beyond the adjacent end of its transverse support, means detachably securing each sub-frame element to its support, a table top superimposing said sub-frame elements and detachably secured thereto spaced thereabove, three guides in alignment depending below said table top adjacent to the top thereof, the two end guides of said three being disposed within the space underneath the table top above the two sub-frame elements which support the table top, three guides in aligned relationship depending below said table top adjacent to the bottom thereof, the two end guides of said three being disposed within the space underneath the table top above the two sub-frame elements which support the table top, a pair of stringers adapted

to be received end-to-end within the three guides at the top of the table top, the abutting ends of said stringers being disposed within the intermediate of said three guides, a pair of stringers to be received end-to-end within the three guides at the bottom of the table top, the abutting ends of said stringers being disposed within the intermediate of said three guides, said stringers projecting beyond the ends of the table top, end extensions for said table supported upon said stringers, a pair of end extensions for each sub-frame element, each end extension being of a stepped formation and having one end portion adapted to be received within the depending guide, means underneath said sub-frame element and having its opposite end portion adapted to abut against the end of said frame element and forming an aligned end extension thereof, a table top wing supported upon said end extensions at the top of the table top, a table top wing supported upon said end extensions at the bottom of the table top, and means securing said wings to said end extensions at the top and the bottom of the table top.

GEORGE R. COLE. 25
